UNITED STATES PATENT OFFICE.

WILLIAM L. DAYTON, OF FORT WORTH, TEXAS, ASSIGNOR TO GRAVITY PUMP AND POWER CO., OF FORT WORTH, TEXAS.

PUMP-JACK.

1,309,843.

Specification of Letters Patent. Patented July 15, 1919.

Application filed March 20, 1918. Serial No. 223,483.

To all whom it may concern:

Be it known that I, WILLIAM L. DAYTON, a citizen of the United States of America, residing at Fort Worth, in the county of 5 Tarrant and State of Texas, have invented certain new and useful Improvements in Pump-Jacks, of which the following is a specification.

My invention relates to pump-jacks and 10 more particularly to certain gravity-actuated means for increasing the power of the pump-jacks, and the object is to provide gravity-actuated devices for operating on levers and means for causing the greatest 15 leverage on the upstroke of the sucker rod and for causing the least leverage on the down stroke of the sucker rod. Another object is to provide a power saving attachment for pump-jacks or means for aiding 20 the driving power of the pump-jacks. The advantage is that a much smaller motor can be used to operate the pump-jack and the attachment may be used on other devices than pump-jacks, as for well drilling 25 machines. Other objects and advantages will be fully explained in the following description and the invention will be more particularly pointed out in the claims.

Reference is had to the accompanying 30 drawings which form a part of this application.

Figure 1 is a side elevation of a single-acting pump-jack provided with the attachments. Fig. 2 is a plan view of the same.

Fig. 3 is a side elevation of a double-acting pump-jack which embodies the attachments shown in the previous views. Fig. 4 is a plan view of the same. Fig. 5 is an end elevation of the pump jacks shown in Figs. 3 and 4.

Similar characters of reference are used to indicate the same parts throughout the several views.

The pump-jack is provided with a frame 45 in two parts 1 and 2 which parts are substantially duplicates. Each part may be a single casting or formed of a single piece. The two frame members are connected and braced by sleeved rods or bars 3, there being 50 two of such bars on one end of the frames and three bars on the other end. The frames will also be connected and braced by the operating shafts. A power wheel 4 is provided with a shaft 5 which is journaled 55 in the frame members 1 and 2 and a balance

wheel 6 is mounted on shaft 5. A pinion 7 is rigid with shaft 5 and this pinion drives a cog wheel 8 which is rigid with and drives the main crank-shaft 9. A link bar 10 is pivotally connected to the crank-shaft 9 and 60 is driven by this shaft. The link bar 10 is to be connected to the sucker or other pull rod. The drawings show a crank 11 rigid with shaft 9 for operating a temporary or demonstrating pump 14. The crank 11 is 65 connected to a link bar 12 which is connected to the sucker rod 13 of the pump 14. The crank-shaft 9 is driven by the power wheel 8 through shaft 5, pinion 7 and cog wheel 8.

The gravity attachments are connected to 70 the shaft 9 and consist of a lever 15 which is rigid with shaft 9 and a sliding weight 16 is mounted on the lever 15. The weight 16 is shifted on the lever 15 by means of a crank 17 and a link bar 18 which is pivotally connected to the weight 16 and pivotally connected to the crank 17. The crank 17 is rigid with the pivot bolt or shaft 19 and a spur pinion 20 is rigid with the bolt 19 and meshes with and is driven by a spur pinion 80 21 which is rigid with frame 1. An adjustable weight 22 may be mounted on the lever 15 for increasing or decreasing the power of the lever.

Upon rotation of the shaft 9 and the 85 lever 15 carrying the pinion 20, the latter will have a planetary movement around the fixed pinion 21 and also a rotation on its own axis due to its meshing with the pinion 21 which is fixed.

When the pump jack is in action the weight 16 will be automatically actuated or shifted by the gearing 20 and 21 and the crank 17 and link bar 18. The weight 16 is shifted toward the end of the lever 15 on 90 95 the upstroke to aid in lifting the load and shifted toward the shaft 9 when there is no need of much power or when less power is required on the down stroke of the sucker-rod.

The pump jack shown in Figs. 3 and 4 is 100 adapted for operating two sucker rods instead of one. The gravity attachments are duplicates of the gravity attachments previously shown. The pump-jack is provided with two 105 frame members 25 and 26 which may be braced by connecting bars 27. The frames will be braced by the fulcrum bars 28 and 29 and by the power shaft 30. An off-set bearing 31 is provided on each frame member for 110

the power shaft 30. A power wheel 32 and a balance wheel 33 are rigid with the shaft 30. The shaft 30 drives pinions 34 which are rigid therewith. The pinions 34 drive 5 cog wheels 35 which are mounted on shafts or stub shafts 36 which are provided with bearings 37 formed on the frame members 25 and 26. The cog wheels 35 drive or cause to be actuated walking beams 38 and 39. 10 The walking beam 38 is connected to one wheel 35 by a pitman rod 40 and the walking beam 39 is connected to the other wheel 35 by a pitman rod 41 so that the walking beams 38 and 39 are positively driven from 15 the power shaft 30. The walking beams 38 and 39 may be used to drive the type of double acting pumps which have one sucker rod running within the other.

Means are provided for aiding the power-driven shaft 30. Power arms or levers 42 and 43 are rigidly mounted on the stub shafts 36 and turn with these shafts. Sliding weights 44 and 45 are mounted on the arms 42 and 43 respectively. Pinions 46 are 20 rigid with the frame members 25 and 26 and mesh with pinions 47 which are rigid with pivot bolts or shafts 48 which are journaled in the short arms of the levers 42 and 43. Cranks 49 and 50 are rigid with the 25 pivot bolts 48 and pitman bars 51 and 52 are pivotally connected to the weights 44 and 45 and to the cranks 49 and 50 respectively. The weights 44 and 45 are shifted in the same manner as the weight 16 is shifted. 30 The weights 44 and 45 are shifted toward and from the fulcrum or stub shafts 48 by the gear wheels 46 and 47 respectively. When the work ends of the walking beams 38 and 39 are at their lowest points, the 35 weights 44 and 45 are at their highest points ready to aid the walking beams on the up-stroke to bring up the loads.

What I claim, is,—

1. A pump jack comprising a frame, a 45 power shaft journaled in said frame, a crank shaft journaled in said frame and gearing for driving said crank shaft from said power shaft, a sucker rod to be actuated by said crank shaft, a lever rigid with 50 said crank shaft, a slidable weight mounted

on said lever, a crank provided with a pivot shaft journaled in said bar, and gearing on said crank shaft and on the pivot shaft of said crank for actuating said crank to reciprocate said weight on said bar. 55

2. A pump jack comprising a frame, a power shaft journaled in said frame, a crank shaft journaled in said frame and gearing for driving said crank shaft from said power shaft, a sucker rod to be actuated by said 60 crank shaft, and gravity attachments for aiding in driving said crank shaft consisting of a lever rigid with said crank shaft, a weight slidable thereon, a crank provided with a pivot shaft journaled in said lever, 65 a gear wheel rigid with said crank shaft and a gear wheel mounted on the pivot shaft of said crank and driven by the first mentioned gear wheel for actuating said crank, and a link bar pivotally connected to said crank 70 and to said weight for reciprocating said weight on said lever.

3. A pump jack comprising a frame, a crank shaft journaled in said frame, means for driving said crank shaft, and gravity 75 attachments for aiding in driving said crank shaft consisting of a bar rigid with said crank shaft, a weight slidable thereon, a crank pivotally connected with said bar on the opposite side of said crank shaft from 80 said weight, gearing for actuating said crank from said crank shaft, and a link bar pivotally connected to said crank and to said weight for reciprocating said weight on said bar. 85

4. A pump jack comprising a frame, a crank shaft journaled in said frame, means for driving said crank shaft, and gravity attachments for aiding in driving said crank shaft consisting of a bar rigid with said 90 crank shaft, a weight slidable thereon, a crank pivotally connected to said bar, gearing for actuating said crank from said crank shaft, a link bar pivotally connected to said crank and to said weight, and an adjustable weight mounted on said bar. 95

In testimony whereof, I set my hand, this 21st day of January, 1918.

WILLIAM L. DAYTON.
